UNITED STATES PATENT OFFICE.

MELCHIOR ARMATO, OF CHICAGO, ILLINOIS.

SOLDERLESS-CAN-CAPPING MACHINE.

Application filed March 31, 1923. Serial No. 628,968.

To all whom it may concern:

Be it known that I, MELCHIOR ARMATO, a citizen of the United States, residing at Chicago, in the county of Cook and State of Illinois, have invented a certain new and useful Improvement in Solderless-Can-Capping Machines, of which the following is a specification.

My invention relates to cap closure applying apparatus whereby cans and other containers may be sealed without the use of solder, my purpose more particularly being to improve the construction of the can sealing apparatus disclosed in my prior application, Serial Number 471,184, by providing a more simplified arrangement of parts, by providing for adjustment of parts, and by providing for the complete manipulation of the apparatus by the operator's foot whereby his hands remain free to accomplish rapid and expeditious application and removal of containers to and from the apparatus.

With the foregoing and other purposes in view, my invention consists in the novel features of construction, combination and arrangement of parts as will be hereinafter more fully described, illustrated in the accompanying drawings and defined in the appended claim.

30 In the drawings wherein like characters of reference denote corresponding parts in the different views

Figure 1 is a side elevation of can sealing apparatus embodying the novel and essential features of my invention;

Figure 2, a front elevation;

Figure 3, an enlarged detail view partly in vertical section of the crimping mechanism;

40 Figure 4, a detail section through one of the rods;

Figure 5, a detail section on the line 5—5 of Figure 3;

45 Figure 6, a detail section on the line 6—6 of Figure 3; and

Figure 7, an enlarged view showing the can sealed.

With particular reference to Figure 7 of the drawings it will be observed that a can or other container of the type adapted to be sealed by the mechanism constituting my invention is provided initially with an opening bordered by an upwardly extending flange, while the cap that is adapted to close this opening is provided with a marginal channel that receives said flange, the purpose

of my improved apparatus being to bend or crimp the metal constituting said flange and forming said channel in such manner as to provide a fluid tight seal between the can and cap without the use of solder or other sealing substances.

A preferred embodiment of my improved mechanism or apparatus for accomplishing the foregoing purpose as illustrated in the drawings consists of a standard 10 that is extended laterally at its upper end to provide a journal or support 11 for a vertical shaft 12, which shaft has mounted thereon, above the support 11, a bevel gear 13 that meshes with a similar gear 14 on an electric motor 15 whereby said shaft is driven. Gear 13 bears either directly or indirectly against the upper face of the support 11 to hold the shaft against downward movement, but may be secured in different positions along the shaft whereby the latter may be longitudinally, i. e. vertically adjusted. Below the support 10 said shaft has threaded thereon a collar 16 that bears either directly or indirectly against the under face of the support to hold the shaft against upward movement, said collar being adjustable along said shaft to permit vertical adjustments of the shaft with respect to its support.

At its lower end shaft 12 terminates in an enlarged head or sleeve 17, the bottom portion of which is of cylindrical shape, while its top portion is of conical shape, being flared upward and outward to provide a cam 18. Within the bore 19 of this sleeve is slidably fitted the upper end of a preferably but not necessarily cylindrical member 20, which member is caused to rotate with said sleeve by a pin 21 on one of these parts engaging in a slot 22 in the other part, said pin and slot connection permitting sliding movement of the member into and out of the sleeve within predetermined limits as is obvious. An expansion coil spring 23 between the sleeve and member normally urges the latter to its outermost or downward limit of movement with respect to the sleeve.

The member 20 below the sleeve 17 has threaded thereon a collar 24, which collar is provided with opposed lugs 25 carrying pins 26 on which are intermediately pivoted substantially vertically extending levers 27, the upper ends of which terminate adjacent to the cam 18, while their lower ends carry rollers 28 in the form of dished disks that are arranged at an inclination upward and

outward with respect to the axis of the member 20 as shown. The upper end of each lever has threaded therein a screw member 29 that is provided with a ball head 30 for engagement with the cam 18 whereby said cam functions, when the member 20 is moved upward within the sleeve 17, to move the upper ends of said levers outward and as a consequence to move the rollers 10 inward. The screw members 29 are for the purpose of securing adjustment to cause a greater or lesser amount of inward movement of the rollers proportionately to equal amounts of upward movement of the member 20. Lock nuts 31 are provided whereby desired adjustments of the screw members may be maintained. Normally the lower ends of the levers 27 and the rollers carried thereby are urged relatively outward and 20 the members 29 maintained in contact with the sleeve by a single spring in the form of a bowed inherently resilient member 32 that extends around the member 20 and at its ends engages with and presses outward 25 against said levers. The collar 24, being threaded on the member 20 is adjustable longitudinally of the member whereby further adjustability between the levers and the cam is provided, a set screw 33 being 30 provided to lock said collar in selected adjusted position.

The shaft 12 is hollow and the member 20 is provided with a bore, and extending through said shaft and the bore of said member is a rod 34. This rod at its lower end is provided with a die 35 in the form of a horizontally arranged disk that is engageable within a can cap to be crimped and the peripheral edge of which is curved upward and outward for cooperation with the rollers 28 to effect the crimping operation, it being observed in this connection that by dishing the upper faces of the rollers, clearance is provided between said upper faces 45 and the die when the rollers are moved inward during crimping of the cap. The member 20 and the rollers carried thereby are rotatable around the rod 34 and the die 35 and the latter is held against rotation as 50 by means of a block 35' that is secured to the rod and has a forked end 36 non-rotatably but slidably engaging a rib 37 on a gear housing case or bracket 38 fixed to the support 11. The rod is slidable through 55 the shaft 12, but is held against sliding movement relative to the member 20 by means as indicated at 39. Consequently, when pressure is applied against the bottom of the die to move the rod upward, member 20 also is moved upward, and when 60 the spring 23 acts to move member 20 downward, the rod and die also are moved downward. An anti-friction bearing 40 is provided between the upper face of the die and 65 the lower end of the member 20 whereby

turning movement of the member is substantially unresisted by the die.

Mounted for longitudinal movement within suitable bracket arms 41 extending laterally from the standard 10 is a vertical 70 rod 42 that is disposed preferably in axial alignment with the rod 34 and at its upper end carries a plate 43 on which a can 44 to be sealed is adapted to be seated. On said rod 42 is secured a block 45 having spaced 75 lugs between which operates one end of an intermediately pivoted lever 46, the other end of which is connected by a link 47 with a foot treadle 48 whereby downward pressure on said treadle serves to elevate the 80 can. A spring 49 secured at one end to the link 47 and at its other end to the standard 10 serves to urge the rod 42 normally downward.

The operation of my improved mechanism is apparent and is as follows: The motor 15 being in operation, a can to be sealed with a cap disposed in covering relation to the flanged opening in the top thereof, is seated on the plate 43 and pressure 90 applied to the treadle 48 to elevate the can. As the can is thus moved upward, the die 35 is received in the cap and the latter is first forced home over the flange on the can and an initial shaping imparted to the cap and flange by the upwardly and outwardly flared periphery of the die. Upon continued upward movement of the can, the die, and with it the rod 34 and member 20, are moved upward, causing the rotating levers 100 27 to coact with the rotating cam 18 to move the rotating rollers 28 inward against the cap and flange and thus coact with the die to crimp and seal the cap. Upon release of the foot treadle, spring 23 moves 105 the member 20, die 35 and rod 34 downward to their original position and spring 32 operates to move the rollers 28 outward away from the cap, all parts of the mechanism thus being restored to normal position 110 in readiness to again be operated when the sealed can is removed from the plate 43 and another can placed thereon.

The adjustability between the different coacting parts of the mechanism renders the latter capable of effective operation on cans constructed of different weight or thickness of material, while considered in its entirety said mechanism consists of a minimum number of strong, durable parts compactly arranged. Any desired number of rollers may be provided and means other than that illustrated may be provided to elevate the cans, in fact various changes and desirable additions may be made in and to the mechanism disclosed within the scope 115 of my invention as defined in the appended claim.

I claim:

Can sealing apparatus comprising a sup- 130

port, a one-piece rotatable hollow shaft journaled in said support, means to adjust said shaft longitudinally through said support and to hold the same against longitudinal movement from its adjusted position, a sleeve formed on said shaft, a cam surface on said sleeve, an exteriorly threaded member longitudinally slidable within said sleeve, a pin and slot connection between 5 said sleeve and member whereby the two are rotatable in unison and relatively slid- able longitudinally within predetermined limits, means constantly urging said member toward its outermost limit of sliding move- 10 ment with respect to said sleeve, a collar threaded on said member whereby it may be 15 adjusted longitudinally of the member, a pivoted lever carried by and rotatable with said collar, a roller carried by said lever, a rod within and longitudinally movable 20 through said sleeve and shaft, a connection between said member and rod whereby the two are longitudinally movable in unison, a die on said rod engageable within a can cap to be crimped, and a cooperative con- 25 nection between the cam on said sleeve and said lever whereby inward longitudinal movement of the die, rod and member moves said roller towards said die.

In witness whereof, I have hereunto sub- 30 scribed my name.

MELCHIOR ARMATO.
